APPARATUS FOR CONTROLLABLY ADJUST-
ING DIE PARTSJohn L. Olson, Minneapolis, Minn., assignor to
Dahlstrom Mfg. Co., St. Paul, Minn., a partnership

Application November 12, 1949, Serial No. 126,720

10 Claims. (Cl. 76—4)

1

This invention relates to apparatus for controllably adjusting the relative positions of the portions of a die.

More specifically, it relates to apparatus for controllably raising and lowering a punch holder portion of a die, for locking said punch holder at any desired elevation, and for freely rotating said punch holder on both vertical and horizontal axes.

In the past the requirement involved in die setting for repeated separation and bringing together of the parts of a die has been met by manually lifting the parts of the die into position and then manually separating them again, thereby requiring an expenditure of physical effort of considerable proportions. When the manufacturer receives the die, the two parts are generally received with their complementary faces in contact just as they will be when in operation. These faces are held tightly and rigidly in position by huge telescoping guide posts extending between their respective base plates or beds, the upper bed of which is normally called a punch holder and the lower of which is normally called a die shoe. Before the steel or cutting elements of the die can be set within the complementary faces, it is necessary for the manufacturer to pry the two faces apart. To do this, it is essential that the punch holder portion be lifted along a line precisely normal to the plane of the die shoe. This is true because the guide posts are necessarily extremely close fitting to insure that the punch holder will always lower the cutting elements disposed thereon to precisely the same position relative the co-operating elements disposed on the die shoe. If lifted even a very slight amount more on one edge than the other, the guide posts will wedge and cause extreme difficulty in again attaining free telescopic movement. Previously, this initial separating has been done with considerable effort with a pry bar accompanied with a great deal of hammering, with the result that the two faces were frequently badly battered before any of the steel was ever set in the faces of the die. My invention eliminates this undesirable practice and provides for an easy means of separating the two faces without marking either even slightly.

In setting a die it is necessary to set the various cutting elements of the die and their cooperating members into the base plates or beds of the die in very precise positions. This requires approximate setting of these elements, the bringing of the upper and lower portions of the die toward each other and approaching operating

2

position for examination to determine whether the element is properly positioned, their separation again to reset the cutting element to a position closer to that desired, and so on until it is located in the precise position required. This means that the faces of the die must be brought into approximate operating position for examination a number of times for each cutting element or steel before it is finally positioned correctly.

10 Given a large die which normally has a large number of cutting elements, the amount of physical effort required for repeated separations of the die parts is considerable if attempted manually as has been the normal procedure previously. The amount of time consumed by this procedure is excessive and unnecessary. Sometimes manufacturers attempt to circumvent the manual effort required by inserting the punch holder and die shoe in the punch press and adjusting the steel in the faces of the die while the latter are in position for operation. This is very awkward and unhandy since the distances between the faces when the die is in the punch press is very limited even when in separated position and it requires overhead work to set steel in the face carried by the punch holder. My device eliminates the need for all this inconvenience and needless effort.

Also, it is oftentimes necessary in perfecting a die or in keeping it in perfect operating condition that work be performed on the interior surfaces of the die. This in the past has involved the expenditure of a great deal of physical effort which I have obviated with my structure. It was necessary in the past in order to work on the inside surface of the punch holder portion of the die, that this portion be removed manually and turned upside down or on its side upon a lower surface. My invention eliminates the excessive requirement of physical effort in setting a die as well as the labor involved in removing it for working on the die after it has been properly set and has operated long enough to have become worn.

An object of my invention is to provide apparatus for controllably raising and lowering the punch holder portion of a die directly above the die shoe portion of the die in combination with a set of telescoping guide pins, thereby facilitating the initial separation of the die parts preparatory to the setting of the die and eliminating the deformation normally experienced in this process.

Another object of my invention is to provide apparatus which will rigidly grip the various portions of a die and hold them firmly in place

in any desired position so as to facilitate the setting or repair of the die.

Another object is to provide apparatus for the raising or lowering of the punch holder portion of a die and locking it in any desired position relative to the remaining portion of the die, thereby enabling the die-setter to set steel or cutting elements therein quickly and easily without manually lifting the die parts.

Another object is to provide a device which, in addition to controllably raising and lowering the punch holder portion of a die, will provide for controllable rotation of that portion on both a vertical and a horizontal axis, thereby permitting a die operator to have free access to the die parts while engaged in setting the steel or repairing the die and eliminating the need for lifting the die parts manually.

A further object of my invention is to provide an automatic lock for a rotatable drive shaft normally used in a die jack or the like to controllably adjust the elevation of the punch holder portion of a die relative to the die shoe portion.

These and other objects and advantages of the invention will more fully appear from the following description made in connection with the accompanying drawings, wherein like reference characters refer to the same or similar parts throughout the several views, and in which:

Fig. 1 is a side elevational view of an embodiment of the invention with a die set shown in position in broken lines.

Fig. 2 is a front elevational view of the structure shown in Fig. 1.

Fig. 3 is a vertical sectional view of the structure shown in Fig. 1, with a die set in position in solid lines.

Fig. 4 is an enlarged vertical sectional view of the locking mechanism shown in Fig. 3 with a section broken away to show the key on the opposite side.

Fig. 5 is a cross-sectional view along line 5—5 of Fig. 3.

Fig. 6 is an enlarged vertical sectional view along line 6—6 of Fig. 2.

An embodiment of my invention, as shown in Figs. 1, 2, 3, 4, 5, and 6, includes a rigid upstanding cylinder 10 with a base portion 11 movably mounted on rollers 12 and having a table or pedestal 13 disposed at its upper end. Telescopically mounted within the cylinder 10 is a shaft 14 which carries at its upper end a gripping mechanism 15 comprising two L-shaped slidable clamps 16 and 17 each of which extend through a gripping base 18 in apertures provided therefor and are surrounded by a plurality of bushings 19. The gripping base 18 has a backing plate 20 consisting of a piece of flat metal. The bushings 19 may be caused to tilt or twist on the clamps 16 and 17 by the turning of a handle 21 which causes the flat side 22 of a locking pinion 23 to turn away from the bushings 19 and the rounded portion 24 to twist or tilt the bushings 19 so as to lock the clamps 16 and 17 in place. Mounted on the top portion of the gripping base 18 by means of a heavy threaded screw bolt 25 or other suitable means is a flat bar of metal 26 which extends outwardly to cooperate with a conventional C-clamp 27. The entire gripping mechanism 15 is pivotally mounted on the upper end of the shaft 14 by means of a horizontally disposed bolt 28 which extends from the front side of the backing plate 20 through that plate, another plate 29, the shaft 14, and a housing 30 and is fastened with a nut 31.

Carried by the table member 13 is a gripping mechanism 32 similar to the mechanism 15 but in inverted position. This mechanism serves to hold in co-operation with the table 13 the die shoe portion 33 of the lower part 34 of the entire die in rigid position. The upper part 35 of the die is held in firm position by the gripping of the punch holder 36 by slidable clamps 16 and 17 in co-operation with the gripping base 18 and by the C-clamp 27 in cooperation with the metal bar 26. The die shoe 33 is connected to the punch holder 35 by two telescoping guide posts 37 and 38 which serve to guide the upper face 39 of the die so as to meet the lower face 40 of the die squarely.

As best shown in Fig. 4, the cylinder 10 carries a housing 41 for a wheel crank-shaft 42 and is formed to provide a seat 43 for a truncated cone section 44 formed on the lower end portion of the shaft 42. Just above the truncated cone portion 44, as shown, is a slightly enlarged section 45 of the shaft 42 having external threads 46 thereon. These threads 46 co-operate with threads 47 of similar depth and pitch formed on the shaft 14 as shown in Fig. 1 to provide an effective worm gear action when the shaft 42 is turned by means of the wheel crank 48. Encircling the shaft 42 just above the threaded section 45 is a coiled spring member 49 compressed by a slidable collar 50 which surrounds the shaft 42 and is keyed to the housing 41. A collar 51 lies just above the slidable collar 50 and is keyed to the shaft 42 by a key 52 to permit limited longitudinal movement of the shaft 42 relative the collar 51 and to preclude rotation of the shaft 42 relative the collar 51. This collar 51, as shown, has recesses 53 formed on two opposite upper sides of its outer portions. The wheel crank base 54 is an additional collar-like member free to rotate about the shaft 42 and has recesses 55 formed in its lower and outer portions to complement those in the collar 51 and to together receive a freely movable key 56 which can be tilted as shown in Fig. 4. The wheel crank base 54 of the wheel crank 48 is rotatably mounted on the shaft 42 at the point 57 in a manner designed to prevent its longitudinal movement relative the shaft 42.

Operation

My invention is easy and simple to operate, yet it effects a substantial saving in time and effort. As described above, the die is normally received with the faces 39 and 40 adjacent each other and the guide posts 37 and 38 telescoped into each other. In order to separate the faces and mount the steel thereon, it is essential that the die parts 34 and 35 be pulled precisely straight away from each other. To accomplish this the die is placed into our device and the clamps 16 and 17 are brought up into snug position against it. The handle 21 is then turned so as to turn the flattened surface of the pinion 23 away and cause the rounded surface 24 to tilt the bushings 19 and thereby wedge the clamps 16 and 17 so as to hold them and the punch holder 36 in proper position. The C-clamp 27 is then placed on the other end of the punch holder 36 and the bar 26 and tightened so as to hold that end of the punch holder firmly. At the same time and in like manner the gripping mechanism 32 is fastened to hold the die shoe 33 firmly on the table or pedestal 13. The die parts are then ready for separation.

To accomplish the separation it is imperative that the punch holder 36 be lifted directly above

and away from the die shoe 33, else the guide posts 37 and 38 will wedge. This is attained by merely turning the wheel crank 48. This, of course, causes the wheel crank base 54 to turn and tilt the key 56 as shown in Fig. 4 so as to lock the shaft 42 to the wheel crank base 54 and at the same time provide an inclined plane for the wheel crank base 54, thereby causing the entire shaft 42 to be lifted outwardly. This outward movement compresses the spring 49 further and at the same time lifts the truncated cone 44 free of the seat 43, thereby unlocking the shaft 42 and making it free for rotation with the wheel crank 48. At the same time the threads 46 of the shaft 42 co-operate with the threads 47 of the shaft 14 to provide a worm gear mechanism and cause the shaft 14 to be lifted upwardly and carry the punch holder with it, thereby separating the two parts 34 and 35 of the die. When the wheel crank 48 has been turned far enough to cause the guide posts 37 and 38 to clear each other the wheel crank 48 is released, whereupon the compressed spring 49 will force the truncated cone 44 to return into snug position with the seat 43 and be held there firmly by friction, thereby locking the entire worm gear mechanism. All of the clamps are then released and the punch holder 36 and die shoe 33 are removed from the device and the various cutting elements or steel and their co-operating members are mounted in approximate position on the faces 39 and 40. Then the die shoe 33 and the punch holder 36 are again placed in the device, as previously described, and the die reassembled to determine whether the steel on the two faces 39 and 40 has been inserted in the precise relative positions required. The two parts 34 and 35 can be brought together in the same manner as they were separated by merely turning the wheel crank 48 in the opposite direction. The key 56 will then co-operate with the collar 51 and the wheel crank base 54 in a similar but reverse manner to unseat the cone 44 and lock the shaft 42 to the wheel crank 48. Generally numerous adjustments in the positions of the steel are required and each adjustment involves assembly and disassembly of the die set to determine whether or not the new position is satisfactory. Each time the die parts are placed in the device the faces 39 and 40 are brought toward each other and tested for precise positions relative each other and then again separated. Each time this procedure is executed our device effects a substantial savings in time and effort.

In order to eliminate the need for removing the die parts 34 and 35 from the device each time an adjustment or repair work is required on the cutting elements or their co-operating members, the gripping mechanism 15 is constructed so as to be rotatable on both horizontal and vertical axes. Once the die parts have been separated far enough for the guide posts 37 and 38 to clear each other, the entire mechanism 15 can be swung to either side since the shaft 14 will merely rotate within the cylinder 10, and, of course, raise or lower slightly depending upon which side it is swung toward. Then by loosening the nut 31 the entire mechanism 15 including the plate 20 and the punch holder 36 can be rotated on the bolt 28 which provides a horizontal axis. Then by tightening the nut 31, the entire mechanism 15 and the punch holder 36 held thereby can be maintained in a position readily accessible for work to be performed thereon. When the work

is completed, the nut 31 is released and the punch holder is swung back into position for reassembly. To accomplish this the wheel crank 48 is merely turned in the opposite direction, thereby unlocking the shaft 42 and enabling the operator to lower the punch holder 36 so that the guide posts 37 and 38 will telescope into each other.

To anyone familiar with die setting the advantages of our structure are readily apparent. It provides a quick and easy method of accomplishing an objective which in the past has consumed a great deal of time and required a substantial amount of physical effort.

15. It will, of course, be understood that various changes may be made in the form, details, arrangements and proportions of the parts without departing from the scope of our invention.

What I claim is:

20. 1. Apparatus for the facilitation of the setting and disassembly of a die comprising a relatively stationary member carrying a guideway, a means carried by said stationary member for gripping and holding in releasable, rigid, substantially horizontal position one part of said die, a relatively movable member engaging said guideway and having a longitudinal axis about which said movable member is rotatable and along which said member moves within said guideway, a means carried by said relatively movable member for gripping and holding firmly in substantially horizontal position the remaining part of said die, said last mentioned means being swingable in a horizontal plane with said movable member as the latter rotates, and a means for adjustably raising and lowering said movable member relative to said guideway to attain aligned, substantially vertical movement of said remaining part of said die relative said first mentioned part of said die.

25. 2. Apparatus for the facilitation of the setting and disassembly of a die comprising a rigid, upstanding member, a second rigid member co-operating with said first mentioned member in close telescoping relationship and being rotatable about an upright axis, a means for gripping and holding in fixed position one part of said die, said means being carried by said first mentioned member, a means carried by said second mentioned member for gripping and holding in rigid, substantially horizontal position the remaining part of said die in vertically spaced relation to said first mentioned part of said die, said last mentioned means being swingable in a horizontal plane with said second rigid member as the latter rotates about the upright axis of said rigid member, and a means for controllably adjusting the relative vertical disposition of first and second mentioned means.

30. 3. Apparatus for the facilitation of the setting and disassembly of a die comprising a rigid, upstanding member, a second rigid member having an upright longitudinal axis about which said second member is controllably rotatable and co-operating with said first mentioned member in close, telescoping relationship, a means for gripping and holding in fixed position the die shoe of the lower part of said die, said means being carried by said first mentioned member, a means carried by said second mentioned member for gripping and holding in rigid, substantially horizontal position the punch-holder of the upper part of said die directly above said lower portion, said last mentioned means being swingable in a hori-

zontal plane with said second rigid member as the latter so rotates and a means for controllably raising and lowering said second mentioned member relative said first mentioned member.

4. Apparatus for the facilitation of the setting and disassembly of a die comprising a rigid, upright, hollow tube, a rigid shaft fitted into said tube and rotatable about its longitudinal axis within said tube, a means for gripping and holding in rigid position the die shoe of the lower part of said die, said means being carried by said tube, means mounted on said shaft for gripping and holding in rigid, substantially horizontal position the punch-holder of the upper part of said die, said last mentioned means being swingable about an upright axis and being movable with said shaft, and a means for controllably raising and lowering said shaft relative to said tube.

5. A die jack for the facilitation of the setting and disassembly of a die comprising a rigid, upright cylinder, said cylinder being hollow and relatively fixed, a rigid shaft snugly fitted into said cylinder, said shaft being controllably rotatable about its vertical axis and being capable of upward and downward movement relative to said cylinder, a means for gripping and rigidly holding in a substantially horizontal position the die shoe of the lower part of said die, said means being mounted on said cylinder, a means mounted on and swingable with the upper portion of said shaft about the vertical axis of said shaft for gripping and holding in a substantially horizontal position the punch-holder of the upper part of said die, and a means for controllably raising and lowering said shaft relative to said cylinder.

6. Apparatus for the facilitation of the setting and disassembly of a die comprising a rigid, upright tube, a rigid shaft fitted into said tube, said shaft being controllably rotatable about its vertical axis and being capable of upward and downward movement relative to and within said tube, a means for gripping and rigidly holding in a substantially horizontal position the die shoe of one part of said die, said means being carried by said tube, a means mounted on the upper portion of said shaft for gripping and normally holding in a substantially horizontal position the punch-holder of the remaining part of said die, said second mentioned means being rotatable about a horizontal axis, and a means for controllably raising and lowering said shaft relative to said tube.

7. The structure set forth in claim 6, said means for controllably raising and lowering said shaft relative to said tube comprising external threads on said shaft and a rotatable crankshaft having external threads thereon and being

mounted adjacent said shaft so that its threads can cooperate with the threads on said shaft to provide a worm gear mechanism.

8. Apparatus for the facilitation of setting and disassembly of a die comprising a rigid, upright, hollow cylinder, a substantially horizontal table carried by said cylinder, a gripping member carried by said table and adapted to cooperate with said table to rigidly hold in a substantially horizontal position the base plate of one part of said die, a rigid shaft fitted into said cylinder, said shaft having external threads on its medial portion and being capable of rotation about its longitudinal axis, as well as longitudinal movement relative to said cylinder, a gripping member carried by the upper portion of said shaft and adapted to normally hold in a substantially horizontal position the base plate of the remaining portion of said die, said second mentioned gripping member and said remaining die portion being swingable in a horizontal plane with said shaft relative to said first mentioned portion of said die and said table, and a rotatable crank-shaft having external threads thereon of depth and pitch equal to that of the threads on said shaft and being mounted adjacent the medial portions of said shaft so that the threads thereon can co-operate with the threads on said shaft to provide a worm gear mechanism for controllably raising and lowering said shaft and the gripping member carried thereby relative to said cylinder and said table.

9. The structure set forth in claim 8 and said gripping member carried by the upper portion of said shaft being also rotatable on a horizontal axis.

10. The structure set forth in claim 8 and a guide post disposed on the inner side of each of said die portions of such dimensions and in such position to permit the telescoping of one of said guide posts into the other when one of said die portions is positioned directly over the other and said shaft is lowered.
